[57] CLAIM

The ornamental design for a combined athletic look shoe and watch, substantially as shown and described.

DESCRIPTION

FIG. 1 is a top plan view of a combined athletic look shoe and watch showing my new design, the bottom of the shoe being of conventional appearance, plain and unornamented;

FIG. 2 is a right side elevational view thereof, the left side being similar but without the watch and strip on the quarter;

FIG. 3 is a top plan view of another embodiment of my new design of FIGS. 1-2, the bottom being substantially flat, plain and unornamented; and

FIG. 4 is a right side elevational view thereof, the left side being similar but without the watch and strip on the quarter.

FIG. 1.

FIG. 2.

FIG.3.

FIG.4.
